UNITED STATES PATENT OFFICE.

MICHAEL Z. SOCHA, OF JOLIET, ILLINOIS.

DESIGN FOR A HAND-SPRINKLER.

48,617.

Specification for Design.

Patented Feb. 22, 1916.

Application filed February 23, 1915. Serial No. 10,144. Term of patent 7 years.

To all whom it may concern:

Be it known that I, MICHAEL Z. SOCHA, a subject of the Emperor of Austria-Hungary, residing at Joliet, in the county of Will and State of Illinois, have invented a new, original, and ornamental Design for a Hand-Sprinkler, of which the following is a specification, reference being had to the accompanying drawing, forming part thereof.

Figure 1 is an elevation of my hand

sprinkler, showing my new design, and Fig. 2 is a plan view of same.

I claim:

The ornamental design for a hand sprinkler, as shown.

MICHAEL Z. SOCHA.

Witnesses:

JOHN VANCRAK,
GEORGE SOCHA.
